AUTOMOBILE HEADLIGHT ANTI-BLINDING LENS

Emile H. Fregeau, 3495 5th Ave. N., St. Petersburg, Fla.

Filed Aug. 11, 1958, Ser. No. 52,149

Term of patent 14 years

(Cl. D48—32)

Fig. 1 is a front elevation of an automobile headlight anti-blinding lens showing my new design;

Fig. 2 is a sectional view thereof taken on line 2—2 of Fig. 1;

Fig. 3 is a sectional view thereof taken on line 3—3 of Fig. 1.

I claim:

The ornamental design for an automobile headlight anti-blinding lens, as shown.
